Inventor

UNITED STATES PATENT OFFICE.

ALBERT W. BRUCE, OF BLOOMFIELD, IOWA.

ROTARY EXPLOSIVE-ENGINE.

1,228,401.

Specification of Letters Patent.

Patented June 5, 1917.

Application filed April 14, 1916. Serial No. 91,094.

To all whom it may concern:

Be it known that I, ALBERT W. BRUCE, a citizen of the United States, residing at Bloomfield, in the county of Davis, State 5 of Iowa, have invented a new and useful Rotary Explosive-Engine; and I do hereby declare the following to be a full, clear, and exact description of the invention, such as will enable others skilled in the art to 10 which it appertains to make and use the same.

This invention relates to an improved rotary internal combustion engine, and an object of the invention is to provide an engine of this kind having simple, improved and practical features of construction.

One of the features of construction is the provision of a casing having intake ports, exhaust ports, and a hollow cylinder valve 20 rotatable in the casing and provided with a port to alternately register with the first ports, for intaking and exhausting the interior of the cylinder valve constituting the combustion chamber, in which the piston 25 is reciprocated.

Another feature of the invention is to provide a multiple cylinder internal combustion engine, in which improved connections are provided between the crank shaft and the 30 combined revoluble cylinder valve and combustion chamber casing, so that when the ports of said valve alternately register with the intake and exhaust ports of the casing, the piston will in turn receive its charge, 35 and exhaust the utilized gases.

In practical fields the details of construction may necessitate alterations, falling within the scope of what is claimed.

The invention comprises further features 40 and combination of parts, as hereinafter set forth, shown in the drawings and claimed.

In the drawings:

Figure 1 is a vertical sectional view through one of the cylinders of a multiple 45 cylinder engine constructed in accordance with the invention, showing the piston, the crank and its connection to the piston of another cylinder.

Fig. 2 is a cross sectional view on line 50 4-4 of Fig. 1, showing one position of the cylinder valve.

Fig. 3 is a similar sectional view showing another position of the cylinder valve.

Fig. 4 is a similar sectional view showing 55 another position of said valve.

Fig. 5 is a similar cross sectional view

showing a fourth position of the cylinder valve.

Fig. 6 is a cross sectional view on line 8-8 of Fig. 1.

Fig. 7 is a cross sectional view of the engine casing illustrating one position of the revoluble cylinder valve, and showing an addition of intake and exhaust ports.

Fig. 8 is a similar cross sectional view of 65 the casing and the revoluble cylinder valve showing the same in another position.

Fig. 9 is a cross sectional view of the engine casing and the cylinder valve showing the same in another position.

Fig. 10 is a cross sectional view through 70 the engine casing showing the addition of intake and exhaust ports, and illustrating the revoluble cylinder valve in another position.

Referring more especially to the drawings, 1 and 2 designate the crank casings of the multiple cylinder engine casings 3 and 4, which casings are bolted together by means of bolts 5. Mounted in bearings of the 80 crank casings 1 and 2 is a crank shaft 6, to which the sprocket 7 is fixed by means of the key or feather 8 that is, between the two crank casings, and upon one end of the crank shaft 6 the drive pulley 9 is mounted. 85 The shaft 6 is provided with the cranks 10 and 11, to which the pitman rods 12 and 13 are connected by means of the cap plates 14 and bolts 15. The upper end of each pitman terminates in the usual bearing sleeve 90

16. The bearing sleeves 16 are pivotally mounted upon the pins 17 on the interior of the pistons 18 and 19. The cylinder casings are provided with the usual cylinder heads 20, which are secured to the upper ends of 95 the cylinder casings by means of the bolts 21.

The cylinder heads 20 and the cylinder casings are provided with the usual water jackets 22, and the usual sockets 23 for the spark plugs 24 and 25. As shown in Figs. 100 2 to 5 inclusive it will be seen that the cylinder casings are provided with intake and exhaust ports 26 and 27, and revolubly mounted in said cylinder casings are

cylinder valves 28 and 29, which are substantially of the same length as the cylinder casings, and are fitted telescopically in said casing, but for revoluble movements comparatively loose therein, and these cylinder valves are provided with diametri-

110 cally oppositely disposed ports 31 and 32, which, as the cylinder valve rotates through

their connections with the crank shaft, said ports 31 and 32 alternately register with the intake and exhaust ports 26 and 27. In other words, when the port 31 registers with the exhaust port 27, the utilized gases are exhausted; therefore the port 31 at this instance will constitute an exhaust port. Then the port 31 will register with the intake port 26, thereby permitting an intake charge, and in this case the port 31 will act as an intake port. The same is true in regard to the port 32 as it registers with first the exhaust port 27 and then the intake port 26. The usual intake and exhaust manifold 33 and 34 are connected to the intake and exhaust ports 26 and 27, as seen in Fig. 1. Mounted in bearings of the upper part of the crank casings is a shaft 35, to which, a sprocket wheel 36 is fixed by means of the pin 37. The collars 38 which are secured upon the shaft 35 by the pins 39 prevent endwise or axial movement of the shaft 35. The sprocket 36 has a sprocket chain connection 40 with the sprocket wheel 7 of the crank shaft. Rotatable with the shaft 35 are worms 41 and 42, which mesh with the worm teeth 43 of the flanges 44 of the lower parts of the cylinder valves 28 and 29. It is to be seen that by virtue of these connections that the cylinder valves 28 and 29 will rotate, in order to correspond with the intake of a charge, the compression thereof, the firing of the same, and finally the exhaust of the utilized gases. Mounted in the wall of each cylinder casing is a stub pin 46, secured in position by the nuts 47, and on the inner end of the stub pin a roller 48 is mounted for engaging the under surface of the flange 44 of each cylinder valve to support the same in position as it rotates. In Figs. 7, 8, 9 and 10 additional intake and exhaust ports 49 and 50 are provided, in which case the intervals between the explosions must necessarily be decreased; hence the gearing between the cylinder valves 28 and 29 must necessarily be changed accordingly, but which altered connections are not shown.

It will be seen that the stub-pin 46 previously referred to has its two ends offset with respect to each other, giving it the shape of a crank. By the roller 48 being on this cranked end, the stub-pin 47 can be loosened in the casing and the roller 48 adjusted to compensate for any longitudinal wear that may have occurred in the cylindrical valve.

Operation.

In so far as the operation of this engine is concerned, it is only necessary to set forth the operation of one cylinder, it is to be understood that the pistons of both cylinders alternate in their cycles of operations. Referring to the piston 18, it is to be seen that as said piston starts on its downward

stroke, one or the other of the ports 31 and 32 is beginning to register with the intake port 26, thereby sucking in a charge. After the piston 18 reaches the end of its down intake stroke, either one of the ports 31 and 32 has passed out of registration with the intake port 26. The piston 18 then starts on its upward compression stroke, compressing the charge. Immediately following the completion of the compression stroke, the charge is fired, as a result of which the piston moves downwardly. The piston, after completing the firing stroke, starts upon its upward stroke, just about, or substantially a little after one or the other of the ports 31 and 32 begins to register with the exhaust port 27, thereby exhausting the utilized gases. Therefore, substantially at the time the piston completes its exhaust stroke and instantly subsequently starting on its next intake stroke, one or the other of the ports 31 and 32 is beginning to register with the intake port 26. It is to be noted that the gearing between the crank shaft 6 and the cylinder valve is of such design and construction as to operate the cylinder valve so that said ports will register approximately at the time as above set forth, it to be understood that the pistons of both cylinders 95 carry out the foregoing cycles of operation alternately. In an engine involving the construction and arrangement of intake and exhaust ports such as shown in Figs. 7 to 10 inclusive, it is to be understood that the 100 gearing between the crank shaft 6 and the cylinder valve should be so designed and constructed as to rotate the cylinder valves of both cylinders at faster rates of speed than the cylinder valves shown in Fig. 1, 105 owing to there being just double of intake and exhaust ports to those shown in Figs. 2, 3 and 4 and 5. The gearing for providing this increase of speed can consist of the same parts as disclosed in Figs. 1 and 6, with the 110 exception that the teeth and threads of the worm wheels and the worms may be constructed on a greater pitch.

The invention having been set forth, what is claimed as new and useful is:

1. In an internal combustion engine, a cylinder, a piston working in the cylinder, a cylindrical valve telescopically arranged in the cylinder and surrounding the piston, means for continuously rotating the valve 120 during the normal operation of the engine, inlet and exhaust ports for the cylinder, diametrically disposed ports in the cylindrical valve, said ports acting alternately as inlet and exhaust ports and arranged to 12 register with the inlet and exhaust ports of the cylinder in such a way that when one port in the cylindrical valve acts as an intake for a certain charge the diametrically opposite port in the cylindrical valve 13

will perform the exhaust function for the same charge, and means to secure the cylindrical valve against longitudinal movement, said means comprising an adjustable device attached to the engine casing which device can be operated from the outside of the casing to compensate for any longitudinal wear in the cylindrical valve.

2. In an internal combustion engine, a cylinder, a piston working in the cylinder, a cylindrical valve telescopically arranged in the cylinder and surrounding the piston, means for continuously rotating the valve during the normal operation of the engine, 15 inlet and exhaust ports for the cylinder, diametrically disposed ports in the cylindrical valve, said ports acting alternately as inlet and exhaust ports and arranged to register with the inlet and exhaust ports 20 of the cylinder in such a way that when

one port in the cylindrical valve acts as an intake for a certain charge the diametrically opposite port in the cylindrical valve will perform the exhaust function for the same charge, and means to secure the cylindrical valve against longitudinal movement, 25 said means comprising an adjustable device to compensate for longitudinal wear in the cylindrical valve and being composed of a cranked stub-pin pivotally adjustable in the engine casing and a roller adapted to engage the flange of the cylindrical valve.

In testimony whereof I have signed my name to this specification in the presence of two subscribing witnesses.

ALBERT W. BRUCE.
